DESIGN FOR A KNITTED BLOUSE.

Application filed November 29, 1926. Serial No. 19,867. Term of patent 14 years.

To all whom it may concern:

Be it known that I, WILLIAM A. KELLER, a citizen of the United States, and resident of Cleveland, county of Cuyahoga, and State of Ohio, have invented a new, original, and ornamental Design for a Knitted Blouse, of which the following is a specification, reference being had to the accompanying drawing, forming part thereof.

In said annexed drawing:

Fig. 1 is a front elevational view; Fig. 2 is a fragmentary back elevational view of the blouse shown in Fig. 1.

The present sweater design consists of a body of solid color having cuffs of stripes

of a contrasting color and having a bottom band portion likewise having stripes of a contrasting color. The blouse is made with a substantially round neck opening and a V-shaped piece of knitted material is secured to the blouse around such neck opening but spaced therefrom, this band extending completely around the neck and made with stripes of contrasting colors.

I claim:

The ornamental design for a knitted blouse as shown and described.

Signed by me this 27th day of November, 1926.

WILLIAM A. KELLER.
